(57) **CLAIM**

The ornamental design for: dual caliper braking components for rear wheel drive vehicle, as shown and described.

DESCRIPTION

FIG. 1 is a front elevational view showing my new design for a dual caliper braking components for rear wheel drive vehicle;

FIG. 2 is a right side elevational view thereof;

FIG. 3 is a rear elevational view thereof;

FIG. 4 is a left elevational view thereof;

FIG. 5 is a top elevational view thereof; and,

FIG. 6 is a bottom elevational view thereof.

1 Claim, 3 Drawing Sheets

FIG. 2

FIG. 1

FIG. 4

FIG. 3

FIG. 5

FIG. 6
